UNITED STATES PATENT OFFICE.

ANTHONY F. McDONNELL, OF DUNMORE, PENNSYLVANIA.

BOTTLE AND CAP-CLOSURE.

No. 893,008.

Specification of Letters Patent.

Patented July 14, 1908.

Application filed March 31, 1908. Serial No. 424,396.

To all whom it may concern:

Be it known that I, ANTHONY F. McDONNELL, a citizen of the United States, residing at Dunmore, in the county of Lackawanna 5 and State of Pennsylvania, have invented certain new and useful Improvements in Bottles and Cap-Closures; and I do hereby declare the following to be a full, clear, and exact description of the invention, such as 10 will enable others skilled in the art to which it appertains to make and use the same.

The general object of my invention is to provide an improved form of bottle and cap-closure therefor, particularly adapted for the 15 reception and secure retention of gaseous liquids, such as beer and the like.

As a subsidiary object may be mentioned the peculiar construction of lever provided with trunnions or bearing ends engaging the 20 bottle and curled or looped, whereby a smooth bearing surface is presented to prevent chipping of the glass, and, at the same time, a larger bearing surface is gained, which distributes the pressure on the glass 25 by the locking-lever when sealing.

Two important objects, also, in my invention, are, first, to obviate the presentation of a projection or protuberance interiorly of the bottle-neck, in the region of the trunnion- 30 sockets, and, second, in providing the trunnion-sockets, to shape them so as not to weaken the glass at these points, but yet have them of sufficient depth for the trunnions to secure a firm grip. I am aware of certain 35 devices patented in the prior art which are impracticable for the very reason that their constructions present the objections just noted. Bottles for bottling beer and other gaseous drinks are always purchased for per- 40 manent service; that is, the bottler uses the same bottles over and over again, continuing their use by re-filling them until they are broken or lost. The bottles must be so made that they can be rapidly and easily cleaned, 45 which work is usually done by means of a revolving brush of rubber or hair, which is inserted in the bottle-neck and revolved at a very high speed. Now, with trunnion-sock- 50 etes in bottles as commonly made, forming

projections interiorly of the neck, rapid filling or cleaning of the bottle is impossible. In bottling beer, or other gaseous liquids, a metal tube attached to a machine, is inserted through the neck and extends about 55 five inches into the bottle. The diameter of this tube must be at least one-half inch,

even for slow filling. It is obvious that bottles with interior projections cannot be filled by this method without utterly destroying the bottle. Further, a bottle with interior 60 projections cannot be rapidly or satisfactorily cleaned by any known method, as the revolving brush, when being inserted, or when being revolved, will snap off the projections. With my construction, I obviate 65 the presentation of protuberances interiorly of the bottle-neck, at the same time maintaining the required strength of the glass at the trunnion-sockets.

One of the distinguishing features of my 70 invention is the peculiar construction of the bottle whereby both of the trunnion-sockets are not at the poles of a line bisecting the circular neck of the bottle; that is to say, suppose a diameter line were drawn from one 75 socket, it will be found that, in my device, the opposite socket is to one side, slightly, of the other end of the diameter line. By experiment, in my business as a practical bottler and glass-bottle manufacturer, I have 80 found that this is the only arrangement by which the lever will work properly and effect even pressure on the sealing-disk.

Another object of my invention is to construct a device which shall be exceedingly 85 simple of construction, which is thoroughly efficient in operation, which is easy to manipulate, which is strong and durable in use, and which can be manufactured and sold at a 90 moderate cost.

With these objects in view, the invention comprehends the novel construction, combination, and arrangement of parts of a device characterized by my invention, as will be 95 fully hereinafter described in the specification, summed up in the claims, and illustrated in the drawings.

In the drawings; I have shown a device capable of carrying out the fundamental and underlying principles of my invention, it being understood that other forms of embodiment may be used and many modifications in detail may be made, without affecting the operation or the advantages of the device, and without departing from the spirit of the 105 invention.

In the drawings: Figure 1 is a view in side elevation, partly broken away, of one form of my bottle; Fig. 2 is a vertical section, on the line 2—2, Fig. 1; Fig. 3 is a horizontal section, on the line 3—3, Fig. 1; Fig. 4 is a detail view of the cap, Fig. 5 is a view in side

elevation, partly broken away, of another form of my invention; and Fig. 6 is a horizontal section, on line 6—6, Fig. 5.

Referring, now, to the drawings in detail, 5 A designates a bottle provided with a neck a , preferably encircled exteriorly by a flange a^2 , merging at two points into annular flanges a^3 , forming sockets a^4 . Both of these sockets are not at the poles of the diameter of the 10 neck, supposing the diameter line to be drawn from one of the sockets. The socket opposite the one from which the diameter line is drawn is disposed slightly to one side of the other end of the diameter line; since I have, 15 by experiment, found that this is the only arrangement by which the lever may work properly and effect, through the bail, an even pressure on the sealing-disk; if the sockets are at the poles of the diameter, the action of 20 the locking-lever throws the bail off center when sealing, and the bail has a tendency to drag the cap to one side. These objections I overcome by my peculiar arrangement. These annular flanges a^3 I consider an important element of my invention, going to make 25 up the ultimate perfection of the whole device. The provision of these flanges obviates molding the glass of the neck, at these points with depressions, which would greatly 30 weaken the glass of the neck at these points, and which would, also, require the provision of projections interiorly of the neck around such molded depressions, such projections or protuberances being liable to inevitable 35 breakage in the operation of cleaning the bottle, or otherwise. By the provision of my annular flanges a^3 , also, I retain, unimpaired, the original thickness and strength of the glass at the neck of the bottle, which is a de- 40 sideratum, owing to the unusual strain on the glass of the bottle-neck by the action of the trunnions of the locking-lever, in the operation of sealing the bottle. By the provision of these annular flanges a^3 , projections 45 interiorly of the neck, at the region of the sockets, are obviated.

In the top of the bottle-neck, there is formed an annular groove a^5 .

B designates my improved sealing-cap, 50 comprising an annular disk b provided with a top lug b^2 , having an eye b^3 , and with an annular flange b^4 to engage the top of the bottle-neck. Depending from the flange b^4 are a plurality of spaced prongs b^5 , in this instance 55 three being shown. On the under surface of the disk b , disposed centrally thereof, there is what may be termed a "hub", b^6 . Also formed on the under surface of the cap, between the flange b^4 and the hub b^6 , are annular grooves b^7 , b^8 , forming therebetween an 60 annular rib b^9 .

Passing through the eye b^3 is a bail b^{10} , its ends engaging the loop b^{11} of a locking-lever b^{12} , in the usual manner. The ends of the 65 locking-lever are curled or looped, as shown

at b^{13} , and constitute trunnions, which are sprung into the sockets a^4 .

Any kind of a sealing-disk or washer may be used with my cap-closure, but, from the standpoint of cheapness, I prefer to use, instead of cork, or the like, paper, as shown at 70 b^{14} . The rib b^9 forces the paper into the groove a^5 , and the hub b^6 exactly fits in the bottle-neck; the trunnions, by reason of the fact that they are curled or looped, present a 75 broad bearing surface on the sockets and distribute the strain; the peculiar disposition of the sockets, one of them being to one side of the diameter line, as described, permits proper working of the locking-lever and an even 80 pressure on the sealing-disk b^{14} ; and, by reason of the relative arrangement, construction, and combination of parts of my device, the cap B seals the bottle easily and perfectly without strong pressure on the locking- 85 lever b^{12} .

From the foregoing description and detailed analysis of my invention, taken in connection with the drawings, the many practical advantages thereof are obvious and will 90 appeal, particularly, to those skilled in the art to which the invention appertains.

In Figs. 5—6, I have shown a construction of bottle especially adapted for larger-mouth bottles, such as milk-bottles and the like. 95 This form of my invention closely resembles and parallels that species shown in Figs. 1 to 4, excepting that lugs or pintles c , c are formed centrally in the sockets a^4 , engaging which are the curled or looped ends of the 100 trunnions of the locking lever.

The purpose of the flange a^2 , in the device of Figs. 1 to 4, is to guide the locking-lever ends b^{13} to their sockets a^4 , in the operation of attaching the locking-lever to the bottle. 105 Further to guide the ends b^{13} into the sockets, I preferably provide the flanges a^3 with shallow grooves a^6 (Fig. 1), so that the ends b^{13} , in sliding along the shoulder a^2 , will pass into the grooves a^6 , being guided by the latter 110 into the sockets a^4 .

Having thus fully described my invention, what I claim as new and desire to secure by Letters-Patent is:

1. A circular neck bottle formed with two 115 exterior annular flanges, forming sockets, one socket being disposed to one side of the end of a diameter line drawn through the neck from the other socket.

2. A bottle formed with two exterior annular flanges, forming sockets, and a locking-lever provided with trunnions having its ends disposed in the sockets. 120

3. A bottle formed with two exterior annular flanges, forming sockets, a locking-lever provided with trunnions having curled ends disposed in the sockets, and a sealing-cap provided with an annular circumferential flange and, on its under surface, with a central hub portion, with two grooves between 125 130

the hub and said annular flange, and with a rib separating the two grooves and a bail carried by said cap and operatively connected to said locking-lever.

5. 4. A circular-neck bottle formed, on its neck, with two exterior, annular flanges, forming sockets and provided with top, transverse, shallow grooves, said neck being also formed with an additional annular flange extending from said two annular flanges and encircling said neck, and a locking-lever provided with trunnions having curled ends disposed in said sockets.

10. 5. A bottle formed with two exterior annular flanges, forming sockets, a locking-lever provided with trunnions having curled ends

disposed in the sockets, and a sealing-cap provided with an annular circumferential flange and, on its under surface, with a central hub portion, with two grooves between the hub and said annular flange, and with a rib separating the two grooves; said circumferential flange carrying depending prongs and a bail carried by said cap and operatively connected to said locking-lever.

20. 25. In testimony whereof, I have hereunto set my hand, in the presence of two witnesses.

ANTHONY F. McDONNELL.
